Primary Examiner — Michael A. Pratt*Assistant Examiner* — Michelle E Wilson(74) *Attorney, Agent, or Firm* — Boyle Fredrickson, S.C.(57) **CLAIM**

The ornamental design for a bicycle wash and fill station, as shown and described.

DESCRIPTION

FIG. 1 is a first perspective view of the bicycle wash and fill station, showing the new design.

FIG. 2 is a second perspective view of the bicycle wash and fill station of FIG. 1.

FIG. 3 is a front view of the bicycle wash and fill station of FIG. 1.

FIG. 4 is a back view of the bicycle wash and fill station of FIG. 1.

FIG. 5 is a top view of the bicycle wash and fill station of FIG. 1.

FIG. 6 is a bottom view of the bicycle wash and fill station of FIG. 1.

FIG. 7 is a first side view of the bicycle wash and fill station of FIG. 1; and,

FIG. 8 is a second side view of the bicycle wash and fill station of FIG. 1.

The broken lines depict environmental subject matter only and form no part of the claimed design.

1 Claim, 4 Drawing Sheets(56)
